Atty's:

UNITED STATES PATENT OFFICE.

HAROLD G. TREGILLUS, OF BARRINGTON, ILLINOIS.

GIRDER.

1,330,771.

Specification of Letters Patent. Patented Feb. 10, 1920.

Application filed April 28, 1919. Serial No. 293,160.

To all whom it may concern:

Be it known that I, HAROLD G. TREGILLUS, a subject of the King of Great Britain, and a resident of Barrington, in the county of 5 Cook and State of Illinois, have invented certain new and useful Improvements in Girders, of which the following is a specification.

My invention relates to girder, rafter or 10 truss structures for supporting roofs, canopies and other loads, and for use in bridges and similar structures. Structures of this class usually comprise an arch member, a chord member and intervening connecting 15 and strengthening members.

The arrangement must be such that the arch will retain its proper curvature even though the load thereon is irregularly applied. Unless this is accomplished, an arch, 20 supported at its ends upon abutments and loaded only on one side of its center, will deflect downward under the load, while the portion not so heavily loaded will rise above the original line of curvature.

25 The object of my invention is to produce a girder that is economical, rigid and applicable to a variety of purposes. This I accomplish by a construction requiring only tension members for adequately maintaining 30 the curvature of the arch under any irregular or eccentric loading. In accordance with my invention tension members in the form of wires, rods or other material connecting the arch abutments or other rigid supports with the arch at such points that 35 under unequal load distribution on the arch the tension members will prevent rising of the arch at certain points, which rising would otherwise result if the load were unbalanced. The tension members of my improved construction in effect serve the same purpose as balance loads which might be placed on the arch at points where the arch 40 would tend to rise owing to the unbalanced load.

45 The preferred form of my invention comprises an arch member, abutment members therefor and the tension members extending between the abutment members and the 50 arch. The structure can be of wood, metal

or combination of wood and metal, or the structure after being built up of metal can be embedded in concrete, the tension members and other members of the metal structure then serving as reinforcement for the 55 concrete.

The various features of my invention are clearly illustrated on the accompanying drawing, in which—

Figure 1 is a side elevational view of my 30 improved structure.

Fig. 2 is an enlarged vertical sectional view of one end of the girder structure.

Fig. 3 is an enlarged view of a section of 65 the arch showing the manner of connection of the tension members therewith.

Fig. 4 is a sectional view on plane 4—4 of Fig. 3.

Fig. 5 is a sectional view on plane 5—5 of 70 Fig. 2, and—

Fig. 6 is a diagrammatic illustration of the operation of my invention.

The structure shown comprises the arch part 10, the supporting blocks 11 for the arch ends, the chord tension member 12 and 75 the tension members 13 intervening between the chord member and the arch. In the structure shown the arch is built up of layers of wood in the form of boards secured to each other by suitable means such as nails, 80 and this arch seats at its ends in the recesses 14 formed in the end blocks 11, the arch and blocks being rigidly secured together by means of strap bolts 15 receiving the blocks and extending upwardly alongside of the 85 arch ends to receive washer plates 16 which are clamped against the arch top by the nuts 17. The chord member 12 may be in the form of a metal bar and extends longitudinally through the end blocks 11 and receives the nuts 18. The blocks 11 may be of 90 wood or metal as desired.

The tension members 13 may be in the form of wires or rods and connect between the end blocks 11 and the arch at predetermined points. Fig. 2 clearly shows the manner of anchoring the ends of the tension members, the members extending through the openings 19 in the blocks 11 with their ends secured in suitable manner 100

to the blocks as by bending back over the top of the block and applying by staples or other fastening means. Where the end blocks are of wood suitable protection is provided by the insertion of metal thimbles 5 in the inner ends of the blocks and caps 20 at the corners around which the tension members are bent. Figs. 3 and 4 show a simple manner of connecting the tension 10 members to the arch by means of eye-bolts 22 extending through the arch and through which the tension members are threaded.

In the structure above described only the arch itself is under compression when the 15 structure is under load, the chord member 12 and intervening members 13 being only under tension. The chord member prevents spreading of the end blocks and the tension members prevent distortion of the arch and 20 maintain its curvature under all load conditions.

Fig. 6 clearly illustrates the purpose and operation of the tension members. *a* represents the arch at its normal curvature and 25 supported by abutment members represented by the arrows *b* and *c*. Suppose now that a load represented by the arrow *d* is applied near one end of the arch, the tendency will be for the arch to flatten at this point and 30 bulge at some other point, it being impossible for the arch to flatten at one point without bulging at some other point.

My invention is based on the principle that if bulging is prevented at one place 35 then flattening will be prevented at some other place where a load is applied. In Fig. 6 the dotted line shows the flattening and bulging of the arch if no means were provided for preventing this distortion. 40 This distortion is prevented in my improved construction by the tension members. In Fig. 6 I have shown two such tension members *e* and *f* leading from the point *g* respectively to the end abutments *b* and *c*. 45 Under effect of the weight *d* the arch will tend to bulge at the point *g* but the tension rods applied at this point will prevent this bulging and therefore flattening of the arch at the point of application of the load *d* will 50 be prevented. Any number of such tension members may be provided in a girder structure and thus bulging at any point will be prevented during the application of a load. These tension members when considered 55 with the chord member *h* would in effect form a Bollman truss inverted and with posts omitted. When the tension members are stressed, the member *h* would ordinarily be in compression, but the loading which 60 produces stress in the tension members, also tends to spread the arch and thus nullifies the compression which would otherwise be in the member *h*, leaving a net result of tension. While the Bollman truss is the pre-

ferred type for the girder described, other 65 types may be used to suit conditions, the basic principle being that the inverted truss is for the purpose of additionally loading the arch.

The tie members 13 in the form of rods 70 or wires may each have separate connection with the arch, or as shown in Figs. 3 and 4 pairs of such members may be formed by single lengths of wire or other stock extending 75 from one abutment block through an eye-bolt and to the other abutment block. Also instead of having the structure partly of wood and partly of metal, it could be constructed entirely of metal or entirely of wood.

The girder of my invention is simple and strong and economical of labor and materials. It is of light weight and can therefore be easily handled. It can be readily assembled either in the shop or at the place of use. 85

Having described my invention, what I claim and desire to secure by Letters Patent is:

1. A truss structure comprising an arch, abutments for the arch ends and a plurality 90 of tension members connecting each of said abutments with said arch members at various points throughout its length.

2. A truss structure comprising an arch, a chord, and web members, said web members forming a plurality of triangles having in common the entire chord for a base, and the arch joining the apexes of the said triangles.

3. A structure of the class described comprising an arch member, positive anchoring means, and tension means operatively connecting one point of said anchoring means with said arch member at various points throughout its length. 100

4. The combination of an arch and an inverted truss so disposed that the compression chord of the inverted truss becomes the tension chord of the arch, the arch being operatively connected at various points 110 throughout its length to the inverted truss.

5. A truss structure comprising an arch and a plurality of members radiating from one end of the arch and forming chords for sections of the arch. 115

6. The combination with an arch, of a plurality of members radiating from one end of the arch and at their other ends connected with the arch at various points thereof.

7. An arch structure comprising an arch, and a plurality of tension members extending from each end of the arch and connected therewith at intermediate points.

8. A structure of the class described consisting of an arch member, and tension members arranged in pairs and connected to the ends of the arch member in common to intermediate points on said arch member. 120

9. In a truss structure, the combination of an elastic arch member, abutments under the ends thereof, said arch member alone supporting loads and transmitting the 5 weights thereof to said abutments, said arch member unless restrained tending to distort and bulge under irregular loading, and restraining members anchored independently

of said arch member and connected therewith to restrain such distorting or bulging 10 and to maintain the arch curvature thereof.

In witness whereof, I hereunto subscribe my name this 24th day of April, A. D., 1919.

HAROLD G. TREGILLUS.
